UNITED STATES PATENT OFFICE

EMIL JAGENBERG, OF DUSSELDORF, GERMANY

MEANS FOR THE MANUFACTURE OF PAPER BOXES, CARDBOARD BOXES, AND THE LIKE

Application filed September 2, 1926, Serial No. 133,112, and in Germany December 3, 1925.

This invention refers broadly to improvements in means for the manufacture of paper-boxes, card-board-boxes and the like containers, and it is particularly intended to devise means of applying the reinforcing or strengthening strips to the corners of such boxes, cartons and the like, and to generally improve and facilitate the process of manufacture and to produce a product of greater durability and applicability than generally obtainable heretofore. In the well known methods of manufacture of such boxes and the like, as practiced heretofore it has been the usual practice to paste the adhesive reinforcing strips from the outside upon the connecting edges of the boxes, which procedure, however, entails difficulties and inconveniences in many cases, as for instance in the case of fancy and artistic boxes. For various purposes it is for instance the common practice to provide the paper- and cardboard boxes with printed and similar matter or with embossed and decorative or ornamental portions, in which case the subsequent pasting of the edges by means of applying a strip or the like to the corners or outer edges destroys the appearance of the box, unless the nature of the connecting strips is very carefully adapted to the character of the printing or ornamentation. This problem, however, presents various difficulties, and it is obvious that the pasting will not stick, if for instance a painted box is used. These difficulties may be avoided according to my invention, and various other advantages are accomplished by applying the pasting strips solely at the inside of the boxes, so that they will not be readily detected in the finished boxes. Even in those cases in which the box in the unfinished condition is provided at its corners with exterior pasting strips, it is of advantage to first apply the connecting strips at the inside, so as to obtain a perfectly smooth exterior surface for the even and secure application of the exterior strips. It is also possible according to this invention to have the inside pasting of previously printed boxes to be performed by the consumer himself, so that the cut-out pat-

terns for the boxes in the flat condition may be delivered to the consumers or customers, whereby a considerable saving in space and freight expenses is realized. But the pasting strips may also be applied as heretofore to the outside of the boxes according to this invention, and in accordance with a modified construction of the invention it becomes possible to apply the pasting strips simultaneously both to the outside and to the inside of the boxes.

In the accompanying drawings illustrating the invention,—

Figs. 1 is a side elevation of a box making machine embodying the invention.

Figs. 1^a, 1^b and 1^c are, respectively, sections on lines 1^a—1^a, 1^b—1^b and 1^c—1^c of Fig. 1.

Fig. 2 is a front elevation of the same.

Figs. 3, 5 and 7 are vertical sections through the anvil and die and related portions of the machine, showing the same in different working positions.

Figs. 4, 6 and 8 are front elevations of the parts as shown respectively in Figs. 3, 5 and 7.

Fig. 9 is a vertical section through the anvil, die and knives.

Fig. 10 is a view of a finished box.

Figs. 11, 12 and 13 are detail views of the cutting knives.

In the construction disclosed the anvil 1 is composed of a relatively narrow, rigid center portion 31 and movable lateral portions 32 which by means of pins 33 are guided in inclined slots 34 of the center part 31 and are forced upwards by the springs 35. The upper surfaces of the parts 31, 32 have a roof-like inclination in such a manner that, when the sections 32 are lowered, their upper surfaces will complement the surface of the section 31 so as to form a continuous angular anvil surface. The upper inclined marginal portions of the parts 32 are provided with recesses or interruptions 36 forming narrow teeth.

On the part 31 there are rotatably journaled interengaging lever like toothed segments 37 on pins 37' in cut-outs 32' of parts

32 and extending with their pins 38 into these parts. (Fig. 1^a). Upon the parts 32 being moved downwardly by the stamp 40, 41, there will always ensue an even displacement parallel to the oblique slots 34 as on pressure upon either part 32 by oscillation of the segments both parts will be positively taken along. The part 31 is telescopically guided in the machine frame 48 and may be locked in adjusted position by any suitable means.

The pressing die 2 which is connected to the carriage 39 is composed of two sections 40, 41—the latter section 41 is guided horizontally, so as to be easily movable along the section 40 and upon the inner terminal head portion of the section 41 a knife blade 42 with V-shaped edge is secured. (Fig. 13). A spring 43 forces the part 41 with the knife 42 against the counter knife 44 (Fig. 11). This knife 44 possesses two spacedly superimposed V-shaped cutting edges 45, 46 and is secured to a slide member 47 which is vertically displaceable on a guide body 48' fixed 25 in the machine frame 48 and is forced upwards by means of a spring 49. On the pressing die 40, a roller 50 is disposed which upon the descent of the die 39 strikes against a lever 51 which by means of a lever 52 moves 30 the slide 47 with the knife 44 downwards. As the counter knife for the knife edge 46 of the knife 44 a knife 53 (Fig. 12) is secured to the guide body 48'.

On the machine frame 48 there are provided two staggered transport means 54, 55, in the form of rollers 61, 62 and 63, 64 respectively, for the reinforcing strips 56, 57. The rollers are rotated in any well known manner, not shown here, upon starting the machine, until the strips 56, 57 have been advanced between the anvil and the stamp the distance of the box height, whereby they pass through the openings 58, 59 of the knives 44 and 53. The strips 56, 57 are 45 gummed, the strip 56 on its lower face and the strip 57 on its upper face. On the strips running through between the rollers 61—64 they are bent thereby into V-shape, and simultaneously they are moistened by the rollers 62 and 64 which dip into the water tanks 65, 66 in such manner that the adhesive matter on the strips is softened and made sticky. On strip 57 the moisture permeates the paper structure and softens the adhesive.

55 This apparatus operates substantially as follows: The anvil is so adjusted that the box 60 with its inner edge portion mounted thereon is adapted to impinge against the knife 44, if the bottom of the box rests upon the 60 head surfaces of the anvil sections 32. The position of the anvil herein shown corresponds to the treatment of the largest sizes of pieces of work. If shallower boxes are to be operated upon, the anvil must be moved 65 inwardly. Since on such displacement the

teeth between the recesses 36 of the anvil parts 32 would be pushed against the stationary knife 53, the parts 32 before displacement of the anvil must be depressed by hand downwardly, and are only freed after the anvil has been moved inwardly, whereupon they will be lifted again by the springs 35. The knife 53 will then be arranged between two of the teeth 36. If desired, the teeth may also be displaced. After the boxes 60 have been mounted in position the driving means are operated causing the pasting strips 56, 57 to be first advanced, and the strip 56 to be disposed above and the strip 57 below within the box. (Figs. 1 and 2.) Thereupon the pressing die 39, 40, 41 is depressed. This causes the knife 42 to cut off the strip 56 which drops upon the edge of the box (Figs. 3 and 4) and upon the further descent of the pressing die 41 its pressing surface places itself upon the outer strip 56 and upon the box 60 and upon the lateral anvil sections 32, whereupon the roller 50 strikes the lever 51 which latter causes the descent of the knife 44 by which means the inner strip 56 is likewise cut off which places itself upon the central anvil portion 31 (Figs. 5 and 6). The continued movement of the pressing die 41 with the box 60 and the pasting strip 56 does not take place any more in the vertical direction, so as to avoid the interior pasting strip 57 being glued to the box in a position so as to project beyond the box for the thickness of the knife 44. In view thereof the parts 41, 56, 60, 36 and 32 are now angularly moved to the rear, in which movement the anvil sections 32 are positively and slidingly guided in the slots 34, while the die section 41 provided with an inclined head surface is subsequently forced down in accordance with the inclined surface 61 of the knife 44 (Figs. 7 and 8). In the lowest position corresponding to Fig. 8 the rear edges of the anvil, of the pressing die, of the box and of the two pasting strips are exactly in the same plane, so that a neat and entirely unobjectionable piece of work in accordance with Fig. 10 is obtained.

It has already been pointed out that the invention is also applicable to operation with one pasting strip only in which case only a simple exterior stitching or a simple interior stitching will be provided.

The invention has been described and illustrated herein with reference to a form of construction as exemplifications of the materialization of its principles, but it should be understood that the invention is not restricted thereto, but may find expression in other modified forms of construction, and changes and alterations may occur in accordance with varying local conditions and the convenience of the user and the kind of material under treatment and the article to be produced, all such modifications and changes

being embraced by the scope and spirit of the claims as hereunto appended.

I claim:

1. In a device of the kind described in combination a three-sectioned lower substantially roof-shaped supporting die for the box, a sectional upper pressing die in alignment with the lower die and terminally angularly recessed opposite the other die, cutting means for said dies and means to guide separate strips of reinforcing material in the direction of the dies and between the same for application to different surfaces of the box.
2. In a device of the kind described in combination a pressure die and a sectional supporting die in axial alignment and cooperating therewith and comprising a central upwardly roof-shaped member and two sectional lateral, downwardly inclined spring actuated members adapted for angular downward movement with relation to the central member and means to guide reinforcing strips of material between said dies and between the sectional lateral members.
3. In a device of the kind described in combination, a sectional supporting die, comprising relatively longitudinally movable sections, a sectionally longitudinally movable pressure die, means to relatively move said dies axially with relation to each other, cutting means on the longitudinal movable section of the pressure die, a counter knife, adapted to follow the movement of the pressure die adjacent the cutting means thereof, and a relatively stationary knife adjacent the counter knife, means on the pressure die for moving the counter knife, and means to guide reinforcing strips between the dies and into engagement with the knives and cutting means.
4. In a device of the kind described in combination, a sectional lower supporting die, comprising relatively longitudinally and angularly movable sections, a sectionally longitudinally movable upper pressure die, means to relatively move said dies axially with relation to each other, angularly recessed cutting means on the longitudinally movable section of the pressure die, a downwardly angularly recessed and bevelled counter knife, a relatively stationary knife adjacent the counter knife, means movable with the pressure die for moving the counter knife, with the pressure die, and means to guide strips of reinforcing material between the dies and into engagement with the knives and cutting means.
5. In a device of the kind described, a lower supporting die and an upper pressure die in axial alignment with the lower die, means to reciprocate one of the dies axially with relation to the other, a longitudinally spring pressed cutting member on the upper die, and spacedly superimposed cutting means adjacent the cutting member and axially vertically movable, a relatively stationary knife, for coaction with said cutting means, and means to guide strips of reinforcing material between the dies and into engagement with the knives and cutting members.
6. In a device of the kind described in combination, a lower supporting die and an upper pressure die in axial alignment with the lower die, means to reciprocate the dies with relation to each other, a longitudinally sprung cutting knife on the upper die, a vertically movable cutting member, adjacent the knife and linked to the upper die, substantially V-shaped superimposed cutting blades on said vertically movable cutting member, a relatively stationary knife coacting with the lower blade of the cutting means, and means to guide superimposed strips of reinforcing material between the dies and into engagement with the cutting means and blade and with the knife.
7. In a device of the kind described, an upwardly roof-shaped supporting lower die, lateral, upwardly substantially laterally inclined side sections, slantingly guided on said lower die, and adapted to complement the roof shaped upper surface thereof, means to move the lateral sections relatively to said lower die and in vertical parallelism therewith, an upper pressure die, longitudinally movable portion on said upper die, means for longitudinally displacing the upper die, cutting means on the longitudinally movable portion of the upper die, counter knives adapted for cooperation with the cutting means and means to guide strips of reinforcing material between the dies and into engagement with the cutting means and the counter knives.
8. In a device of the kind described in combination, a lower supporting die, an upper pressure die, means to reciprocate at least one of said dies in axial alignment with each other, means to guide spacedly superimposed reinforcing strips into engagement with said dies, cutting means, longitudinally movable with relation to the upper strip and operatively connected to the upper die and additional cutting means linked to the upper die, both cutting means engageable with the upper strip and adapted to sever the same, and a relatively stationary knife engageable with the lower strip.
9. In a device of the kind described in combination, a lower supporting die, an upper pressure die, and longitudinally movable sections on said latter die, a knife on said longitudinally movable section, a counter knife, linked to the upper section and cooperating with the other knife, both knives adapted to engage a reinforcing strip, and an additional knife engageable with the lower section and

adapted to engage an additional reinforcing strip.

10. In a device of the kind described in combination, a lower supporting die, an upper pressure die, and a longitudinally movable part on said latter die, a spring actuated knife on said part, a movable counter-knife adjacent said knife, means to feed a strip of reinforcing material between the knives and 10 means to rearwardly displace the movable section after the severing of said strip.

11. In a device of the kind described in combination, a supporting die for an article to be reinforced, a pressure die engageable therewith, a plurality of teeth. In the longitudinal direction of the supporting die and disposed thereon, and adapted for the support and adjustment of articles of different sizes, means to guide reinforcing strips trans- 15 versely onto said dies and into engagement with said article, and cutting means coacting with the dies and operatively engageable with said strips.

12. In a device of the kind described in combination, a supporting die for an article to be reinforced, angularly movable sections on said die, an upper pressure die engageable with the supporting die; a spring-actuatingly, horizontally movable cutting member 25 on the pressure die, an inclined lower terminal portion on the pressure die adapted to cooperate with the angularly movable section on the other die, a counter knife cooperating with the said cutting member and 30 operatively connected to the pressure die and downwardly bevelled, and means to impart a rearward sliding movement to the angularly movable section of the pressure die and to the cutting member on said die.

40 13. A device for attaching reinforcing strips to the corners of boxes, comprising means for guiding a pair of superimposed strips, an anvil and a die movable with relation to each other, and means for operating said parts for applying said strips respectively to the inside and outside of the corner of a box operatively disposed between the anvil and die.

45 14. A device for attaching reinforcing strips to the corners of boxes comprising, in combination, an anvil and a die movable with relation to each other, guiding means for guiding a pair of separate and superimposed strips between said anvil and 50 die, and means for operating said anvil and die for applying strips to the inside and outside surfaces of the corners of a box disposed between said anvil and die.

55 In testimony whereof I affix my signature.
60 EMIL JAGENBERG.
